UNITED STATES PATENT OFFICE.

JOSEPH B. O'DONNELL, OF NEW YORK, N. Y.

CAP ATTACHMENT.

Application filed September 5, 1924. Serial No. 736,107.

To all whom it may concern:

Be it known that I, JOSEPH B. O'DONNELL, a citizen of United States of America, residing at New York city, in the county of Bronx, and State of New York, have invented new and useful Improvements in Cap Attachments, of which the following is a specification.

This invention relates to improvements in cap attachments.

The principal object of the invention is the provision of a device for attachment to a cap of the type having a soft crown, and which device is adapted to hold the crown in its proper shape to prevent sagging of the same at the sides.

Another object of the invention is to provide an attachment which may be quickly applied to a cap or removed therefrom, and which is concealed within the crown of the cap in a manner not to distract from the attractiveness and comfort, but rather add to the neatness and comfort of the same.

A further object of the invention is to provide a cap attachment which is constructed of a soft yieldable material whereby the parts may be bent to various positions of adjustment.

A still further object of the invention resides in the provision of a cap attachment which is simple in construction, cheap of manufacture and highly efficient for the purpose intended.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of my invention per se.

Figure 2 is a top plan view of a cap with a portion of the crown broken away and showing my invention in position thereon.

Figure 3 is an enlarged sectional view on the line 3—3 of Figure 2.

Figure 4 is an enlarged sectional view taken on the line 4—4 of Figure 3.

When wearing caps for sport wear, it has long been the objection that the tendency of the crown of the cap is to sag over at the sides which greatly distracts from the attractiveness of the cap. This is especially true in the light weight caps used for sum-

mer wear which are made of such material as silk, mohair, cotton and the like, and which contain no lining. It is therefor my intention to provide an attachment for caps of the above type which will overcome the objections just mentioned.

Referring more particularly to the drawing, the reference numeral 10 designates my invention in its entirety and which includes a crown supporting member 11, and an attaching means 12. The crown supporting member 11 comprises a length of soft wire bowed to form a front crown supporting part 13, the free ends of which are bent and coiled as at 14 to provide offset members 15 for supporting the sides of the crown of a cap. The coils or members 15 are in transverse alignment with each other to evenly support the crown at opposite sides adjacent the points where the sides of the visor meet the crown.

The attaching means 12 includes a strip of flat material such as tin, and is in the nature of an angular bracket 16. The vertical portion of the bracket 16 is formed with an eye 17 for attachment to the bowed portion of the front crown supporting part 13, centrally thereof. Pivoted to the free end

of the horizontal portion of the bracket is a U-shaped staple 18, the legs of which are inserted through the material from which the crown is formed, after which they are bent toward each other flat against the material to securely hold the attachment against accidental removal.

In Figures 2 and 3, I have shown my invention as applied to a cap A, provided with the usual crown B and visor C. When in position, the horizontal portion of the bracket 16 overlies the underside of the male element which is usually employed in connection with a female element on the visor for holding the front part of the crown in a relatively flat condition. By reason of the front crown supporting part 13, the front of the crown is slightly lifted, while the sides of the crown are prevented from drooping by reason of the offset portions 15. Owing to the resilient nature of the bracket and the crown supporting members, the same may be adjusted by bending them to the desired height at which the crown is to be supported.

From the foregoing description, it will be manifest that my invention may be easily applied or removed from the cap, and when

in applied position, the same is concealed within the crown. In addition to holding the crown in proper shape, the attachment further serves to space the front portion of the crown above the forehead of the wearer to permit free ventilation within the cap.

While I have described what I deem to be the most desirable embodiment of my invention, it is obvious that many of the details 10 may be varied without in any way departing from the spirit of my invention, and I therefore do not limit myself to the exact details of construction herein set forth nor to anything less than the whole of my invention 15 limited only by the appended claims.

What is claimed as new is:—

1. In combination with a cap having a soft crown, a device comprising a single length of material bowed to form a front crown supporting part, the free ends of said 20

length of material being bent to form adjustable side crown supporting members, and attaching means for said device including a bracket for supporting said length of material and a bendable element carried by 25 said bracket and passing through the fabric of said cap, said device being concealed within said crown.

2. A cap attachment comprising a single piece of material bowed throughout its 30 length and having its free ends bent downwardly to form resilient adjustable coils, an angular bracket secured to said piece of material midway between its ends, and an attaching element carried by the free end of 35 said bracket for engagement with the fabric of a cap.

In testimony whereof I have affixed my signature.

JOSEPH B. O'DONNELL.
